UNITED STATES PATENT OFFICE.

CHARLES D. SEEBERGER, OF NEW YORK, N. Y.

ELEVATOR.

1,231,075.

Specification of Letters Patent. Patented June 26, 1917.

Application filed July 8, 1914. Serial No. 849,673.

To all whom it may concern:

Be it known that I, CHARLES D. SEEBERGER, a citizen of the United States, residing at New York, in the county of New York and State of New York, have invented certain new and useful Improvements in Elevators, of which the following is a specification, reference being had therein to the accompanying drawing.

10 My invention relates to elevators, and particularly to an organization in which a solenoid is the actuating means for the elevator-car and also is utilized as a counterbalance to the car.

15 The invention consists in the matters hereinafter described and pointed out in the appended claims.

In the accompanying drawings which illustrate an embodiment of my invention,

20 Figure 1 is a diagrammatic view showing an installation of my invention in an elevator-well or hatchway, parts being broken away along the length of the well for purposes of illustration;

25 Fig. 2 is a view showing an electrically operated counterweight in vertical section and its opposite guides in side elevation;

Fig. 3 is a view partly in side elevation and partly in section of the parts of Fig. 2;

30 Fig. 4 is a view of the parts shown in Fig. 2 with some of them in section and others in top plan;

Fig. 5 is a detail view partly in top plan and partly in cross-section showing a brake;

35 Fig. 6 is a view similar to Fig. 5 showing another brake.

Fig. 7 is a diagrammatic view showing the car provided with a current-reversing switch, and Fig. 8 is a view similar to Fig. 3 showing a polarized switch in circuit with the counterweight.

In the drawings the reference letters A A² represent the side guides of an elevator shaft or well having the usual machine-finished contacting surfaces *a* for the guides *a'* of the car A' and an unfinished web *a²* for the car-brake. The shaft is provided at its top and bottom with sheaves *a³* over each of which a cable *a⁴* runs that is attached at one end to the car and at its other end to the variable counterbalance designated generally by the letter B. These parts are indicated in Fig. 1 in which the structure between the car and counterbalance is broken away to show that the hatch or well may extend any suitable distance through a plural-

ity of floors or landings, and that when the car is at the top of its travel or run the counterbalance will be approximately at the bottom. The car is provided with a starting 60 box and controller *a⁵* having a suitable electrical connection *a⁶* to a source of electrical supply or power (not shown) and also having any suitable means to furnish constant electric current to the guide-rails *b* upon 65 which the insulated guides *b'* of the counterbalance B run. These guide rails are insulatedly attached at their ends to the top and bottom frame-work of the shaft, at one side of the path of travel of the car, which 70 carries a pair of trolley-arms *a⁷* in electrical connection with the controller as shown in Fig. 1 and in contact with the rails to furnish constant current to them.

The counterbalance is made up of a plurality of superposed metallic rings or annulli B' having interior recesses to receive the coils or windings forming the magnetic field, the recesses being formed on their undersides so that the inwardly projecting top 80 edges of the rings will provide pole pieces, the recess in the lowest ring being closed by a plain pole-piece *b²*, all as shown in Figs. 2 and 3. The counterbalance is provided at its top with an insulated head *b³* carrying a 85 pair of spring-pressed trolley-arms C and C' pivoted on plates *c* and contacting with and taking current from the opposite guide-rails *b*. The head and each pole-piece carries an insulated shoe or brush designated by the 90 reference letters D, D', D² and D³ respectively, the brushes facing inwardly and being provided with spring-pressed faces. The brushes D and D² are electrically connected with the trolley C by conductors *x* and *x'*, and the brushes D' and D³ are electrically connected with the trolley C' by conductors *y* and *y'* as shown. The conductor *x* from the trolley C has a branch *z* leading to the top coil of the field, and all of the 95 coils or windings of the rings B' are connected so that the field circuits are in the same direction through the successive coils down to the lowest, which is connected by the conductor *w* to the opposite trolley C', 100 all as shown in Figs. 2 and 3. By this arrangement the field pole pieces are successively positive and negative, the polarity of the pole pieces being determined by the direction of the current in the field. 105

The bore of the counterbalance surrounds with clearance the core designated generally 110

by the letter E, and whose body is composed of a series of hollow iron tubes *e* connected by screw unions *e'* and attached at the top and bottom to the hatchway between the 5 guide rails *b*. If desired the core may be braced at intermediate points by suitable struts in the hatchway and which will swing aside when the counterbalance passes them, such as are now used with traveling cranes.

10 The core is provided with spaced circumferential projections or shoulders *E'* forming pole-pieces, the intermediate recesses containing its coils or windings, and each pole-piece is provided with outwardly extending contacts, here shown in the form of headed-pins *F* and *G*, in electrical connection with the coils or windings of the core and in the path of the field brushes. The direction of the winding of the core 15 includes its poles or magnets in alternative position and negative groups as shown in Fig. 3. By this arrangement the armature or core circuit of each group may be reversed. In the position shown in Fig. 3, for example, when the controller is manipulated to send current to the rails *b* it flows from one rail through trolley *C* and brush *D* to the contact *F* with which this brush is in electrical engagement and down 20 through the armature or core windings to the contact in engagement with the brush *D'* and thence by conductors *y'* and *y* to the trolley *C'* and the other rail, thereby including in this circuit all the poles of the 25 core between the brushes *D* and *D'*; and the current also passes by conductor *x'* to brush *D²* and its contact *F* and the armature windings up to brush *D'* and down to the brush *D³* and out by conductors *y* and *y'* to trolley 30 *C'*, with the result of providing positive and negative poles in the core as shown, the brushes being located to keep the field poles in the lead or advancing ahead of the core poles. At the same time the current 35 from trolley *C* flows through the branch *z* to the field windings thereby magnetizing the field poles of the rings *B'* with the result that the solenoid formed by the rings is pulled along by the magnetic attraction 40 of the opposite poles and the magnetic repulsion of like poles on the core and solenoid to bring opposite poles on the two parts into register. When this occurs the core 45 circuits between the brushes *D*, *D'*, *D²* and *D³* are reversed, and when this reversal of the currents in the core windings occurs all the core poles in the armature circuits 50 change from positive to negative and vice versa. As the solenoid or field poles of the 55 rings retain their original polarity by reason of their current continuing to flow in the same direction through their windings, the solenoid poles are further pulled along by the magnetic repulsion of poles of unlike 60 polarity, this action occurring in all the 65

solenoid poles with the result that the counterbalance is drawn along the core by the successive magnetizing of the coils, and as this reversal of the core circuits will alternately occur by the lead of the field poles 70 as long as the rails *b* are included in the circuit by the operator in the car through the controller *a'* the counterbalance may be made to travel along the core at a speed in proportion to the number and strength of 75 the magnets or the strength of the current.

As the strength of the current to the trolley *C* may be varied by the controller the counterbalancing effect of the parts *B* may be varied and the equilibrium between it 80 and the weight of the car and its load controlled to cause the car to travel. For example, if the car weighs one thousand pounds and its load weighs the same, the counterbalance may be designed to weigh 85 fifteen hundred pounds and the pull exerted by the core on the solenoid composed of the rings of the counterbalance to cause the latter to travel down the core may be increased beyond the difference between 90 them to cause the car to move upward, while when the pull on the solenoid is reduced below the difference in weight of the loaded car and counterweight the car will travel downward by gravity. Also by this invention the electrical operation of the counterbalance in either direction may be accomplished by reversing the direction of the field current by leading it in through the rail coöperating with the trolley *C'* and so 100 causing the counterweight to travel up its core to move the car downward. For this purpose a pole-changer or current-reversing switch *X* in the car may be employed to cut-out the circuit including the brushes *D*, *D'*, *D²* and *D³* and to cut-in the circuit including a second set of brushes *D⁴* having an opposite lead to the first set and contacting with pins *G* in the core windings. By this arrangement the current is led in by the opposite rail *b* and trolley *C'* and passes through the field coils in the opposite direction. As shown for example in Fig. 8, a polarized switch *X'* on the counterweight 110 and appropriately connected in circuit therewith is shifted when the polarity of the circuit is shifted by the pole-changer *X*, and so operates to reverse the circuit through the core as well as to cut-out either set of brushes; the circuit through the core is 115 maintained in the same direction while the switch *X* is set in one position, and is reversed when the switch is shifted. The counterbalance may thus be moved in either direction along its core to raise or lower 120 the car.

The devices disclosed are typical of forms that may be employed, any analogous arrangement of like parts constituting a self-starting motor in which the magnetic attrac- 130

tion and repulsion between the magnetic field of the solenoid comprising the counterweight of the car and the armature or core serves to pull the counterweight along its 5 core to move the car in the shaft.

The elevator car is provided with an electric brake so arranged that when full current is supplied to the rails b the brake will be inoperative and when the current is shut 10 off or fails the brake will operate. In Fig. 5 I show an embodiment of a brake for this purpose, in which the controlling solenoid magnet H is connected in the circuit leading from the controller to the trolleys a^6 as 15 shown in Fig. 1, and the projecting end of the armature or core H' is provided with opposite fixed heads h, h' acting when the core is moved in either direction to compress a coiled spring h^8 located in a suitable container indicated by the reference letter h^4 . The core carries an opposite pair of pivoted 20 toggle arms I to the outer end of each of which a lever arm I^2 is pivoted, and the lever arms are carried laterally and crossed 25 at their pivot joint i' on the underside of the car and with their gripping faces i^2 in the plane of the unfinished web a^2 of the car rails as shown in Fig. 5. When no current is supplied to the magnet H the parts 30 stand in the positions shown in Fig. 5, the expanding action of the spring holding the heads of the core at the ends of the container to cause the brake arms to grip the rails; when current is supplied to the magnet 35 one of the heads of the core (depending on the direction of the current in the magnet) is drawn into the container putting the spring under tension and moving the toggle arms to the corresponding dotted line position 40 and releasing the clamping action of the lever arms on the rail. When the current is shut off or fails the spring returns the parts to the positions shown in Fig. 5 and the brake is set on the rails. It is to be understood 45 that in practice a duplicate brake is provided on the car for each car-rail.

The counterbalance is also provided with a pair of electrically operated brakes co-operating with the rails b , and so arranged 50 that they operate when current is shut off or fails on these rails and are inoperative when full current is supplied to them. In Fig. 6 I show an embodiment of a brake for this purpose in which the controlling magnet K is carried on the lower end of the counterbalance and is in a branch y^2 of the circuit y 55 as shown in Fig. 2. The armatures k are on opposite sides of the magnet pole and are held apart by the intermediate coil spring k' 60 and are loosely pivoted at their outer ends as at m to the ends of lever arms M which straddle the core of the counterbalance and are pivoted at m' with their free ends m^2 in 65 position to grip the rails b . When current is supplied from the controller a^5 to

the counterbalance the magnet K draws the armature or cores k inwardly toward each other to place the spring k' under tension and operate the lever arms to release the grips m^2 from the rail, and when the current is shut off or fails the spring expands 70 to return the parts to their normal positions shown in Fig. 6 to cause the grips to engage the rail. It is to be understood that in practice a duplicate brake is provided on the 75 counterbalance for each rail b .

The brakes on the car and on the counterbalance are controlled by the controller in the car, and the brake-magnets may be made 80 variably sensitive or responsive to an amount or character of current that will not magnetize the field-magnets, so that when the car descends by gravity current may be supplied by the controller to the brake-magnets to prevent the brakes being fully set by their 85 springs and allow the brakes to drag more or less on their rails but which will not excite the field-magnets. By this means the speed of the car in its descent may be governed by the friction of the brakes on their rails, and 90 this may be supplemented if desired by a suitable speed governor S acting on the sheave a^3 .

By this invention I provide an equipoise elevator having an electrically variable counterweight to cause the car to travel in its shaft or well; the movement of the car is caused by magnetic attraction and repulsion between the poles or magnets of the field of the counterbalance and those of its core, 95 and the coils of the core magnets are excited in groups to change the direction of the current in each group by the moving counterbalance through suitable brushes affixed to it and provided with current from 100 the car-controller through the structure on which the counterbalance runs. The descent of the car may be by gravity or by reversal of current in the field, and it may be controlled by the variable brakes, which may be 105 only on either the car or the counterbalance, or on both, and which are electrically operated from the car-controller that governs the counterbalance.

I claim:—

1. In a device of the class described, an 115 elevator car adapted to travel in a shaft, an electrically propelled counterbalance, flexible connections between the counterbalance and the car, said counterbalance comprising a magnetic field and core forming a self-starting motor, guide-rails on which the counterbalance runs, means in the car to supply electric current to either of said rails and means to lead the current from either 120 rail to reverse its direction in the field of the counterbalance.

2. In a device of the class described, an 125 elevator car adapted to travel in a shaft, an electrically propelled counterbalance moving 130

oppositely to the travel of the car, flexible connections between the car and counterbalance, guide-rails on which the counterbalance runs, means in the car to supply electric current to either of said rails, and means on the counterbalance to lead the current from either rail to reverse its direction in the field of the counterbalance.

3. In a device of the class described, an elevator car adapted to travel in a shaft, an electrically propelled counterbalance, flexible connections between the counterbalance and car, guide-rails on which the counterbalance runs, means in the car to supply electric current to either of said rails, and trolleys on the counterbalance to lead the current from either rail to reverse its direction in the field of the counterbalance.

4. In a device of the class described, an elevator car adapted to travel in a shaft, a traveling counterbalance by which the movement of the car is controlled and forming a magnetic field, a magnetic core by which the field is moved to actuate the car, means in the car to energize and deenergize the field, and means on the counterbalance to successively energize the core magnets.

5. In a device of the class described, an elevator car adapted to travel in a shaft, a traveling counterbalance by which the movement of the car is controlled and forming a magnetic field, a magnetic core by which the field is actuated to move the car, an electric-controller in the car in circuit with the field, and brushes on the counterbalance to excite the core magnets.

6. In a device of the class described, an elevator car adapted to travel in a shaft, an electrically propelled counterbalance by which the car is moved in the shaft and comprising a moving magnetic field and a stationary core forming a self-starting motor, guides for the field, means controlled in the car to supply current to the guides, and trolleys on the field contacting with the guides.

7. In a device of the class described, an elevator car adapted to travel in a shaft, an electrically propelled counterbalance moving oppositely to the travel of the car, connections between the car and counterbalance by which the car is moved in the shaft, guide-rails for the counterbalance, an electric current controller in the car, means on the car to supply current to the rails, and means on

the counterbalance to take current from the 55 rails.

8. In a device of the class described, an elevator car adapted to travel in a shaft, an electrically propelled traveling counterbalance by which the car is moved, guide-rails for the counterbalance, an electric-current controller in the car, trolleys on the car in circuit with the controller and the guide-rails, and trolleys on the counterbalance in circuit with the guide-rails and electric propelling devices of the counterbalance.

9. In a device of the class described, an elevator car adapted to travel in a shaft, a traveling magnetic field forming a counterbalance by which the car is moved, a magnetic core by which the field is moved to actuate the car, an electric-controller in the car having electrical connections to energize and deenergize the field and core, an electrically operated brake on the car, and electrical connections between the brake and controller to release the brake when the field is moved.

10. In a device of the class described, an elevator car adapted to travel in a shaft, a magnetic field forming a traveling counterbalance by which the car is moved, a magnetic core by which the field is moved to actuate the car, an electric controller in the car in circuit with the field, an electrically operated brake on the counterbalance, and electrical connections between the brake and controller to release the brake when the field is energized.

11. In a device of the class described, an elevator car adapted to travel in a shaft, a magnetic field forming a traveling counterbalance by which the car is moved, a magnetic core by which the field is moved to actuate the car, an electric-controller in the car in circuit with the field, an electrically operated brake on the counterbalance, an electrically operated brake on the car, and electrical connections between the brakes and controller to release the brakes when the field is energized.

In testimony whereof I affix my signature in presence of two witnesses.
